CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA

DISTRIBUTOR RING

Application filed August 7, 1926. Serial No. 127,878.

My invention relates to distributor rings and particularly to rings for distributing the electrostatic fields about high-voltage insulators.

5 The object of my invention is to provide a ring, of the above-indicated character, that shall permit its easy and economical manufacture from a material of standard form; that shall be readily assembled and mounted 10 in operative position and that shall be simple, durable and effective in its operation.

In high-voltage-insulator practice, it is usual to provide a conducting ring, of one character or another, about the axis of an 15 insulator adjacent to one end thereof to assume flashover arcs and to keep damaging stresses away from the insulating parts.

However, as simple as they may appear, 20 these rings are usually of difficult and expensive manufacture, it being difficult to avoid troublesome operations, such as pipe bending, joint forming and other operations, such as die pressing, which calls for the use 25 of expensive dies.

Certain of these rings have other trouble- 30 some features, such as the joints between the rings proper and the radial arms for supporting them. It is my aim to overcome certain of the objectionable features of distributor rings of the prior art by providing 35 a ring which may be simply and easily made from standard material, such as strap metal, and which shall be uniform and symmetrical in form, economical in manufacture, simple 40 and durable in construction and effective in operation.

Figure 1 of the accompanying drawings is 45 a top plan view of a suspension-insulator unit equipped with a distributor ring of my invention, and

Fig. 2 is a side elevational view of the same.

The device comprises, in general, a high-voltage suspension-insulator unit 1, a sus- 50 pension clamp 2 for attachment to the insulator unit 1 and for supporting a conductor 3, and a conducting-ring structure 4 of my invention for directing and distribut- ing the electrostatic field of the insulator unit 1.

The insulator unit 1 is of the usual and well-known cap-and-pin type and, in this instance, is represented as the bottom unit of a string of similar units for attachment to a supporting tower or structure (not shown). 55

The suspension clamp 2 is also of a usual form, except that it embodies receiving portions 6 for the ring 4 and comprises a channel portion 7 for the conductor 3, a clamping member 8, bolts 9 for holding the clamping member 8 in position and a bridge portion 10 on which the receiving portions 6 and an apertured boss or clevis 11 are disposed. A bolt 12 extends through the clevis 11 and an eye in the insulator pin (not shown). 60 65

The ring 4 comprises, in this instance, duplicate half portions, each constructed of uniform strap-like material having a sector or partial closed-loop-like portion 14 and integral inwardly projecting ends 15 that also project downwardly or out of the plane of the ring. The adjacent corresponding ends or arms 15 of the respective half portions of the ring 4 may be spot welded, riveted or otherwise secured together between the receiving portions 6 and the outer perimeter of the ring and are, preferably, spaced apart and apertured at the extreme inner ends thereof for the reception of bolts 16 and the receiving portions 6 of the clamp 2. 70 75 80

By the above construction, in which specified lengths of strap metal material may be cut from elements thereof and formed into the half rings by simple bending operations, a ring is provided that is not only extremely economical to manufacture but is symmetrical and uniform in shape, simple and durable in construction and effective in operation. 85

While I have shown and described a particular form of my invention, changes may be effected therein without departing from the spirit and scope thereof, as set forth in the appended claim. 90

I claim as my invention:

An electrostatic field distributor comprising a plurality of members each of substantially uniform cross-sectional area throughout having a partial-closed-loop-like field distributing portion and integral bent supporting portions continuing from, and ex- 95 100

tending transversely to, each end of its corresponding distributing portion, said supporting portions extending away from the plane of a closed-loop-like structure formed by said partial-closed-loop-like portions.

In testimony whereof, I have hereunto subscribed my name this 5th day of August, 1926.

CHARLES LE G. FORTESCUE.
